CLAIM

The ornamental design for a drinking vessel, as shown and described.

DESCRIPTION

FIG. 1 is a front perspective view of a drinking vessel; FIG. 2 is a front view thereof; FIG. 3 is a cross-sectional view showing a section taken along line 3-3 of FIG. 4; FIG. 4 is a top view thereof; FIG. 5 is a bottom view thereof; and, FIG. 6 is a top perspective view thereof. The elements depicted in broken lines in the various figures are included for environmental purposes only, and form no part of the claimed design.
